B. BRYNTESON.
PUMP OPERATING MECHANISM,
APPLICATION FILED JUNE 8, 1918.

1,319,640.

Patented Oct. 21, 1919.

UNITED STATES PATENT OFFICE.

BRYNTE BRYNTESON, OF ODEBOLT, IOWA.

PUMP-OPERATING MECHANISM.

1,319,640.

Specification of Letters Patent.

Patented Oct. 21, 1919.

Application filed June 8, 1918. Serial No. 238,984.

To all whom it may concern:

Be it known that I, BRYNTE BRYNTESON, a citizen of the United States, residing at Odebolt, in the county of Sac and State of Iowa, have invented certain new and useful Improvements in Pump-Operating Mechanism, of which the following is a specification.

The invention relates to a pump operating mechanism. The object of the present invention is to improve the construction of pump operating mechanism and to provide a simple, practical and efficient pump operating mechanism of strong, durable and comparatively inexpensive construction adapted to reciprocate positively the vertical pump rods or stocks of a double acting pump.

With these and other objects in view the invention consists in the construction and novel combination and arrangement of parts hereinafter fully described, illustrated in the accompanying drawing, and pointed out in the claims hereto appended, it being understood that various changes in the form, proportion, size and minor details of construction, within the scope of the appended claims may be resorted to without departing from the spirit or sacrificing any of the advantages of the invention.

30 In the drawings:

Figure 1 is a front elevation of a pump operating mechanism constructed in accordance with this invention;

Fig. 2 is a transverse sectional view of the same.

Fig. 3 is a detail view of the pump rod cushioning device.

Like numerals of reference designate corresponding parts in the several figures of the drawing.

In the accompanying drawing in which is illustrated the preferred embodiment of the invention, the pump operating mechanism comprises in its construction a pair of vertical reciprocating rods or stocks 1 and 2 having upper and lower racks 3 which are adapted to mesh with upper and lower pinions 4 and 5 which are located at opposite sides of the pump rods and which are alternately carried into engagement with the same, the pinions at the right hand side of the pump rod being adapted to mesh with the racks for moving the pump rods in a downward direction and the pinions at the left hand side of the pump rods being adapted to mesh with the coacting racks to

impart an upward movement to the pump rods. The upper pinions 4 coact with and actuate one pump rod and the lower set of pinions 5 reciprocate the other pump rod. 60 The pinions 4 and 5 are slidably mounted on and carried by upper and lower slidable supports 6 and 7 which are mounted upon upper and lower portions 8 and 9 of a main or supporting frame 10 which may be of any desired construction and which may be also provided with any suitable means for guiding the supporting members 6 and 7 in their sliding movement to gear the pinions alternately into engagement with the racks of the 70 pump rod.

The pinions are moved simultaneously to carry them into and out of mesh with the said racks and with a master gear 11, suitably mounted upon the main or supporting frame 10 by a shaft or axle 12 and meshing with a driving gear 13, which may be operated from any suitable source of power. The master gear is located between the upper and lower pinions 4 and 5 and it simultaneously engages one of the pinions at the right hand side of the pump rods or stocks and one of the pinions at the left hand side of the same to move the pump rods in opposite directions. When the right hand pinion is in mesh with the rack of one pump rod the latter will be moved downwardly and when the left hand pinion is in mesh with the rack of the other pump rod the same will be moved upwardly. 90

The upper slidable support, which has a limited movement in each direction is locked against accidental movement by means of dogs 15 and 16 to maintain the upper pinions alternately in mesh with the master gear 95 and with the pump rod. The dog 15 which is pivoted or hinged at the outer end as shown is adapted to drop into abutment with the adjacent end of the slidable support 6 when the latter is moved to the right, and it 100 is urged downwardly by gravity and also by a spring 17 of a trip or operating rod 18 having its upper end arranged to lift the pawl or dog 15 and its lower end located in the path of eccentrically arranged projections 19 which are carried by the master wheel 11. The operating rod 18 is arranged in suitable guides 20 of a bracket or block 21 of the main or supporting frame 10 and the lower end or portion 22 of the operating 110 or trip rod 18 is inclined to the vertical and is adapted to be engaged by the eccentrically

arranged lugs or projections 19 whereby when one of the projections comes in contact with the offset portion of the rod 18, the latter will be lifted and will carry the pawl or dog 15 upwardly out of abutment with the 5 slidable support 6 and permit a coiled spring 23 to actuate the said support 6 to carry the left hand pinion out of mesh and the right hand pinion into mesh. The 10 spring 23 which is preferably of spiral form is interposed between a block 24 and an arm 25 which depends from the support 6 at one end thereof. The spring 23 tends to urge the support 6 in one direction and the said 15 support is automatically movable to the left and is actuated by the spring 23 when the pawl or dog 15 is tripped and lifted out of abutting relation with the said support 6 by the eccentric projection 19.

20 The pawl or dog 16 automatically drops into abutment with the right hand end of the support 6 when the latter is moved to the left by the spring 23 and is adapted to be lifted out of such abutment by a trip lever 26 pivoted intermediate of its ends at 27 and having its upper arm arranged to lift the pawl or dog 16. The lower terminal portion 28 of the operating or trip lever 26 is arranged at an inclination to 25 the vertical and is located in the path of the eccentric projections 19 and is adapted to be engaged by the same and swing outwardly to disengage the right hand pawl or dog from the slidable support 6 to enable the said eccentric projection to engage the arm 25 of the said support 6 and move the latter to the right against the action of the spring 23. This will operate to move 30 the right hand pinion out of engagement with the master wheel and the coacting pump rod and carry the left hand pinion into engagement with the said parts.

35 The lower support 7, which is provided with an upwardly extending arm 29, is automatically moved to the right by a coiled spring 30 interposed between the said arm 29 and a block or piece 31 secured to the main or supporting frame 10 at the lower portion thereof. The lower support 7 is 40 held at the limit of its left hand movement against the action of the spring 30 by means of a pawl or dog 32 pivoted intermediate of its ends at 33 upon a suitable block 34 and urged into engagement with the right hand end of the support 7 by a coiled spring 35. The coiled spring 35 is interposed between the outer portion of the pawl or dog 32 and the main or supporting frame and it is adapted to be depressed by an operating or trip rod 36 arranged at an inclination to the vertical and mounted in spaced guides 37 of a block or bracket 38. The upper or inner end of the operating or trip rod 36 has an angularly disposed portion 65 39 inclined to the vertical and located in

the path of the eccentric projections 19 and adapted to be engaged by the same to move the rod 36 outwardly for disengaging the pawl or dog 32 from the lower slidable support 7.

70 The left hand end of the slidable support 7 is engaged by a pawl or dog 40 when the said support is at the limit of its right hand movement and the said pawl or dog 40 when the said support is at the limit of its right hand movement and the said pawl or dog 40 is adapted to be lifted to release the support 7 by means of an approximately L shaped lever 41 fulcrumed at its angle at 42 and having the short arm arranged to 75 lift the said pawl or dog 40. The other arm of the L shaped lever extends upwardly and inwardly at an inclination to the vertical and is arranged to be engaged by a trip or operating lever 43 fulcrumed at an intermediate point at 44 and arranged in substantially an upright position. The lower end of the lever 43 is arranged to engage the L shaped lever and the upper end of the said lever 43 has an angularly disposed portion 45 inclined to the vertical and located in the path of the eccentrically arranged projections 19.

75 The eccentrically arranged projections 19 are located at substantially diametrically opposite points and they are adapted to engage the trip rods and the trip levers to operate the dogs or pawls and have also contacting with the inwardly extending arms 25 and 29 of the slidable supports and 80 move the same against the action of the coiled springs 23 and 30. A reversal of the rack mechanism occurs at each quarter of a revolution of the master wheel, and a continuous reciprocation of the pump rods 85 in opposite directions is effected. The mechanism is applicable to a single pump rod where only one set of pinions will be employed. Each pump rod is provided at a point between the operating mechanism 90 and the pump with a break or joint and is equipped with an air cushion 46 and a spring 47 to cushion and relieve the pump rods of strain and prevent breakage of the same.

95 The air cushioning device 46 comprises a cylinder 48 receiving a piston 49 mounted on the upper section of the pump rod and equipped with a suitable packing 50. The cylinder is provided at its upper end with 100 a head or end wall 51 having a central opening 52 through which passes the upper section of the pump rod and the said spring 47 which is sleeved on the upper section of the pump rod and interposed between the 105 cylinder end wall or head 51 and the suitable stop 52 carried by the upper section of the pump rod and arranged in spaced relation with the cylinder. The cylinder is provided with an upper guide 53 and lower con- 110

verging arms 54 receiving the upper and lower sections of the pump rod. The upper guiding means 53 are preferably in the form of a yoke and the lower arms 54 preferably consist of depending converging portions of the cylinder and are suitably secured to the lower section of the pump rod. The upper and lower sections of the pump rod are connected by a chain 55 or other suitable flexible 10 connection which permits a limited independent movement of the sections to enable the cushioning device to function.

Claims.

1. Pump operating mechanism including 15 a reciprocatory member provided at opposite edges with racks, a master gear, pinions movable into and out of mesh with the racks and the master gear and actuated by the latter to reciprocate the said member, and 20 means for operating the said pinions.

2. Pump operating mechanism including 25 a pair of reciprocatory members provided at opposite sides with racks, pairs of pinions adapted to alternately mesh with the racks to effect a reciprocation of the said members, a master gear located between the pairs of pinions and arranged to be engaged by the same when the pinions are in mesh with the pump rod and means for operating 30 the pinions to carry the same into and out of mesh with the racks and the master gear.

3. Pump operating mechanism including 35 a pair of reciprocatory members having racks at opposite sides, a master gear, a slide- able support, pinions carried by the support and located at opposite sides of the said members and means for actuating the support and carrying the pinions alternately into and out of mesh with the racks and 40 the master gear.

4. Pump operating mechanism including 45 a reciprocatory member having racks at opposite sides, a master gear, pinions located at opposite sides of the said member, a slide- able support carrying the pinions and adapt- ed to move the same into and out of mesh with the racks and the master gear, means for actuating the said support and means for locking the support against movement 50 and for also tripping or releasing the same.

5. Pump operating mechanism including 55 a reciprocatory member having racks at opposite sides, a master gear, a shiftable support, pinions carried by the support and movable into and out of mesh with the racks and the master gear, a spring for urging the support in one direction, means carried by the master gear for moving the support in the opposite direction and means for locking 60 the support and for tripping or releasing the same.

6. Pump operating mechanism including a reciprocatory member having racks at opposite sides, a master gear, a slideable sup-

port, pinions located at opposite sides of the 65 master gear and carried by the support, the latter being adapted to move the pinions into and out of mesh with the master gear and the racks, yieldable means for automatically urging the support in one direction, lugs 70 carried by the master wheel for moving the support in the opposite direction, dogs arranged to hold the support against movement to retain the pinions in mesh and means for releasing the dogs. 75

7. Pump operating mechanism including a reciprocatory member having racks at opposite sides, a master gear, a slideable support, pinions located at opposite sides of the master gear and carried by the support, the 80 latter being adapted to move the pinions into and out of mesh with the master gear and the racks, yieldable means for automatically urging the support in one direction, lugs carried by the master wheel for mov- 85 ing the support in the opposite direction, dogs arranged to hold the support against movement to retain the pinions in mesh and tripping devices located in the path of the lugs and arranged to move the dogs out of 90 engagement to release the support.

8. Pump operating mechanism including 95 a pair of reciprocatory pump rods having upper and lower racks, upper and lower pinions located at opposite sides of the pump rods, a master gear located between the upper and lower pinions, means for carrying the pinions alternately into and out of mesh with the racks and the master gear, means for automatically locking the pinions in 100 mesh and means carried by the master gear for releasing the pinions.

9. Pump operating mechanism including 105 a pair of reciprocatory pump rods having upper and lower racks arranged in pairs, upper and lower pinions arranged in pairs and located at opposite sides of the pump rods, a master gear located between the pairs of pinions, upper and lower slideable sup- ports carrying the pinions, dogs located at 110 the ends of the supports and adapted to en- gage the same automatically to retain the pinions in mesh, a slideable operating rod located at one end of each support and having means for moving the adjacent dogs out of 115 engagement with the support, a lever located at the opposite end of each support and hav- ing means for disengaging the adjacent dog from the support and means for operating the slideable rods and the levers including an 120 eccentric lug carried by the master wheel.

10. Pump operating mechanism including 125 a reciprocating pump rod or member having racks, a master gear, a support having an arm, pinions mounted on the support and located at opposite sides of the pump rod or member and movable into and out of mesh with the master gear and the said

racks, a spring connected with the arm for moving the support in one direction and projecting lugs carried by the master wheel and arranged at substantially diametrically opposite points to engage the arm for moving the support in the opposite direction.

11. Pump operating mechanism including a reciprocating pump rod having racks at opposite sides, a master wheel, a slidable support, pinions carried by the support and movable into and out of mesh with the pump rod and the master wheel, lugs carried by the master wheel, an arm extending from the support into the path of the lugs for effecting a movement of the support in one direction, yieldable means for urging the support in the opposite direction, a pawl or dog for locking the support against movement and an operating device provided with means 20 for disengaging the pawl or dog and having an inclined or angularly disposed portion arranged to be engaged by the lugs prior to

the engagement of the same with the said arm.

12. Pump operating mechanism including 25 a reciprocating member having racks at opposite sides, a slidable support, pinions carried by the support, a master gear arranged to mesh with the pinions when the same are in engagement with the racks, lugs carried 30 by the master wheel, yieldable means for urging the support in one direction, means carried by the support and extending into the path of the lugs for effecting a movement of the support in the opposite direction, a dog for holding the support against 35 movement, an approximately L shaped lever arranged to move the dog out of engagement and an operating or trip lever extending into the path of the lugs and arranged to 40 actuate the said lever.

In testimony whereof I affix my signature.

BRYNTE BRYNTESON.
